Primary Examiner — David Muller*Assistant Examiner* — Nathan Johnston(74) *Attorney, Agent, or Firm* — Dinsmore & Shohl LLP;
Thomas E. Anderson(57) **CLAIM**

The ornamental design for a plaster for tracheostoma, as shown and described.

DESCRIPTION

FIG. 1 is a perspective front view of a tracheostoma plaster device;

FIG. 2 is a front view thereof;

FIG. 3 is a rear view thereof;

FIG. 4 is an end view thereof;

FIG. 5 is an opposite end view thereof;

FIG. 6 is a side view thereof; and,

FIG. 7 is an opposite side view.

The broken line showing of parts of the drawings is included for the purpose of illustrating use and environment and forms no part of the claimed design.
